UNITED STATES PATENT OFFICE

98,617

DESIGN FOR A BUILDING

Frank A. Redford, Horse Cave, Ky.

Application December 17, 1935, Serial No. 60,138

Term of patent 14 years

To all whom it may concern:

Be it known that I, Frank A. Redford, a citizen of the United States, residing at Horse Cave, in the county of Hart and State of Kentucky, have invented a new, original, and ornamental Design for a Building, of which the following is a specification, reference being had to the accompanying drawing, forming part thereof.

I claim:—

The ornamental design for a building as shown.

F. A. REDFORD.
